[57] CLAIM

The ornamental design for a combination toothbrush and tumbler holder or the like, as shown and described.

DESCRIPTION

FIG. 1 is a top, front and right side perspective view of a combination toothbrush and tumbler holder or the like showing our new design;

FIG. 2 is a top plan view thereof;

FIG. 3 is a front elevational view thereof;

FIG. 4 is a right side elevational view thereof, the left side being a mirror image of that shown;

FIG. 5 is a bottom plan view thereof;

FIG. 6 is a top, front, and right side perspective view of a second embodiment thereof;

FIG. 7 is a top plan view of the embodiment of FIG. 6;

FIG. 8 is a front elevational view of the embodiment of FIG. 6;

FIG. 9 is a right side elevational view of the embodiment of FIG. 6, the left side being a mirror image of that shown;

FIG. 10 is a bottom plan view of the embodiment of FIG. 6; and,

FIG. 11 is a top plan view of a third embodiment thereof, the only difference from that of the first embodiment being that it is a mirror image.

The broken-line disclosure of a portion of a wall in the views is for illustrative purposes only and forms no part of the claimed design.

The fragmentary broken line representations of walls in FIGS. 1, 6, 11 and 16, and of holes in FIGS. 11, 13, 16 and 18 are for the purposes of illustration only.
